(57) **CLAIM**

The ornamental design for a camping trailer, as shown and described.

DESCRIPTION

FIG. 1 is a front perspective view of a camping trailer, showing our new design;

FIG. 2 is a back perspective view thereof;

FIG. 3 is a front elevational view thereof;

FIG. 4 is back elevational view thereof;

FIG. 5 is a right side elevational view thereof;

FIG. 6 is a left side elevational view thereof;

FIG. 7 is a top plan view thereof;

FIG. 8 is a back perspective view in an alternate configuration thereof; and,

FIG. 9 is a left side elevational view thereof.

The broken lines illustrate portions of the camping trailer that form no part of the claimed design.
